United States Patent Office.

JOSIAH COBLEY, JR., OF ALLEGHENY CITY, PENNSYLVANIA.

Letters Patent No. 78,862, dated June 16, 1868; antedated June 4, 1868.

IMPROVED FORGING-MACHINE.

The Schedule referred to in these Letters Patent and making part of the same.

TO ALL WHOM IT MAY CONCERN:

Be it known that I, JOSIAH COBLEY, Jr., of Allegheny City, in the county of Allegheny, and State of Pennsylvania, have invented a new and useful Improvement in Forging and Welding-Machines; and I do hereby declare the following to be a full and exact description thereof, reference being had to the accompanying drawings, and letters of reference marked thereon.

My invention consists in so constructing a machine for forging and welding, that its forging and welding-dies, while in action, may be opened and closed to any desired degree, and their force gradually increased or diminished, and adjusted to the work required of them, the whole being constructed, arranged, and operated substantially as hereinafter described.

To enable others skilled in the art to make and use my invention, I will proceed to describe its construction and operation.

In the accompanying drawings, which makes part of my specification—

Figure 1 is a perspective view of my improved forging and welding-machine.

Figure 2 represents a side elevation of the same, with a portion of the base broken away, for the purpose of showing the treadle, and its relation to the other parts of the machine.

Figure 3 is a front view of the dies and guides, and a section of the parts to which they are attached.

Figure 4 is a top view or plan of the treadle.

Figure 5 represents a longitudinal section of the arm D, and transverse of the cam used for imparting a reciprocating motion to said arm.

Figure 6 is a top view of the arm D, and the shifting-guides used for communicating the motion of the treadle to the arm D, without subjecting the treadle to the jerking action of said arm.

In the drawings, A represents the base of the machine, in which is placed the treadle l, which is pivoted at the point, and is connected by the piece n, to the shifting-guides m, which are pivoted on the shaft R, the upper ends of said guides being connected by a pin, O, which passes through a slot, e, in arm D.

To the base, A, is attached the pedestal B, on which are the bearings, 6, of the driving-shaft R, on which are secured the driving-pulley h and cam P, which, revolving in the arm D, gives it a reciprocating motion. The upper end of the arm D is provided with a pin, 8, passing through the piece x, which moves freely in slot g of the lever C, which is pivoted at the point f to the pedestal B.

To the projections A' of the pedestal B and lever C, are secured the dies J and K, the contiguous faces of which are made in form to correspond to the work required of them; in the present case being grooved for the purpose of welding or swaging rods. On the projection A' of pedestal B are attached guides i, to prevent the work from getting between the projections A'.

The operation of my improved forging and welding-machine is as follows:

The driving-pulley h gives a continuous motion to the cam P, giving a reciprocating motion to the arm D, which is supported in the direction of the line marked 5, by the action of the spring S, upon the treadle l, together with the parts connecting it with the arm D. When the arm D is in this position, the lever C will be in the position represented by the dotted line 9, and the die J will be raised sufficiently above the die K for them to receive the work. The treadle l is then pressed down (as represented in fig. 2) by the foot, which, by means of the connecting-rod n, and the shafting-guide m, draws down the arm D, causing it to press the lever C outward, and closing the die J upon the work. The action of the cam P, communicated through the arm D and lever C, will then repeatedly compress the iron. The pressures thus produced may be increased at will by the operator pressing the treadle farther down, he at the same time turning and shifting the work so as to produce the desired form and effect. The arm D will not communicate its jerking motion to the treadle l, through the shifting-guides m, since its only connection with these is by the pin O, which slips easily in the slot e. The treadle l being released, it will be thrown upward by the spring S, raising the arm D, thus bringing it, together

with the lever C, to the position represented by the dotted lines 5 and 9, thereby lifting the die J so that the iron or work may be removed.

Having thus described the nature, construction, and operation of my improvement, what I claim as of my invention, is—

1. Operating the dies J and K by means of the slotted lever C, arm D, and cam P, constructed and arranged substantially as herein described, and for the purpose set forth.
2. The combination of the treadle L, connecting-rod n, and shifting-guides m, when used in connection with the cam P, arm D, and lever C, as herein described, and for the purpose set forth.
3. The guides i, when used in combination with the dies J and K, as herein described and set forth.

JOSIAH COPLEY, JUN.
